JOHN FLAMMANG, OF ST. LOUIS, MISSOURI, ASSIGNOR TO OTTMAR G. STARK, OF ST. LOUIS, MISSOURI.

PROCESS OF MAKING PISTONS.

1,336,689.

Specification of Letters Patent.

Patented Apr. 13, 1920.

Application filed May 23, 1918. Serial No. 236,188.

To all whom it may concern:

Be it known that I, JOHN FLAMMANG, a citizen of the United States, residing at St. Louis, Missouri, have invented a new and useful Process of Making Pistons, of which the following is a specification.

This invention relates to the art of manufacturing pistons.

An object of the invention is to provide 10 a novel process or method of procedure for use in the construction of pistons to be used in engines, motors, pumps and the like, whereby the resiliency of the metal of which the piston is composed may be utilized to 15 press an expansible portion of the piston against the wall of the cylinder in which it is to operate and form a close joint therewith, thus dispensing with the necessity of using piston rings and packing.

20 Another object of the invention is to provide a novel process or method of procedure for manufacturing a piston of a hollow body and an integral top or head which expands by the resiliency of the metal to form 25 close contact with the cylinder wall and thereby dispenses with the necessity of using piston rings or packing.

Other objects will appear from the following description in which reference is 30 made to the accompanying drawing illustrating a piston in different stages of its manufacture, and in which—

Figure 1 is an elevation partly in section of a casting from which the piston 35 may be made.

Fig. 2 is an elevation partly in section of a casting after a portion thereof has been divided into segmental sections and after the casting has been otherwise treated.

40 Fig. 3 is a similar view of the piston casting in another stage of the development of the piston.

Fig. 4 is an elevation of the casting after the supports or connections for the segmental sections of the upper portion thereof have been placed under tension preparatory 45 for the piston to be finished.

Fig. 5 is an elevation of the finished piston.

50 Fig. 6 is a view of the piston mounted within a cylinder for which it is intended, parts of the piston being broken away.

Fig. 7 is a view illustrating one of the details of the piston.

55 In its initial form the casting from which

the piston is made is hollow and consists of the lower ring 1, an upper ring 2, connections 3 integrally uniting the lower and upper rings, bosses 4 integral with the connections 3 through which the holes for the wrist 60 pin are to be formed, a top or head plate 5 integral with the ring 2 and projections 6 extending upwardly from the top plate.

The upper ring 1 and the top plate of the casting are then cut or divided as indicated 65 at 7 (Fig. 2) to divide the upper ring and the top plate into segmental sections which are integrally united with the lower ring 1 by the connections 3. In the form shown the cut 7 extends transversely of the axis 70 of the bosses 4 between the projections 6. Holes 8 are then formed through the connections 3 and the bosses 4. The holes 8 are preferably inclined downwardly toward the inner ends of the bosses. The casting 75 is also preferably, though not essentially, tapered slightly as shown in Fig. 2 in which the dotted lines indicate the original side dimensions of the casting.

Next the wrist pin 9 is inserted in the 80 holes 8 and, due to the inclination of the holes, the placing of the wrist pin forces apart or bends the connections 3, thus separating the segmental sections of the upper portion of the ring. The wrist pin is secured 85 in its mounting by set screws 10.

Next the groove or channel 11 is formed in the head or top plate of the casting, a part of the groove being at each side of the cut 7. The walls of the groove are formed 90 obliquely, being inclined toward each other so that the upper portion of the entrance to the groove is narrower than its base. A key or plate 12 having inclined side edges to match the side walls of the groove 11 is 95 placed in said groove so that when the piston is compressed, as shown in Figs. 4 and 6, the key or plate will be held in the groove. Also keys 13 are seated in grooves in the piston below the ends of the key 12.

100 Either before or after the keys 12 and 13 are placed in the grooves provided therefor the piston is ground or turned and finished as to its outer surface, the lower portion of the piston being formed of a diameter 105 slightly less than the diameter of the cylinder for which it is intended, as shown by dotted lines 14. The top plate and upper ring 2 are finished to a size the diameter of which is equal to the diameter of the cylinder 110

for which the piston is intended, the lines to which the top plate and ring 2 are finished being indicated by the dotted lines 15 in Fig. 4. In the form shown, the piston is held under compression while being finished by bolts 16 passing through the projections 6, the nut 17 on the bolt being turned until the upper segmental sections are drawn to their proper positions, conforming to the positions which they will occupy when in the cylinder.

The finished piston as illustrated in Fig. 5 is provided with a number of circumferential oil grooves 18 in the lower ring 1 and, after being finished, the nut 17 is turned to relieve the tension on the connections 3, thereby permitting the upper ring to open as shown. Also, at some stage in its manufacture the upper edge of the ring 1 is beveled to provide a scraper 19 for the oil, and the lower edge of the ring 2 is also beveled to provide a scraper 20 for the oil. The scrapers 19 and 20 scrape the oil from the surface of the cylinder during upward and downward movement of the piston therein.

When mounted in a cylinder the wall of the cylinder prevents displacement of the keys 13 which are in the form of narrow plates mounted in grooves crossing the cuts 7 below the key 12, thus sealing or closing the cut 7 and preventing the passage of gas, steam or other operating agent. When the piston is under compression a key 12 forms relatively close contact with the side walls 35 of the groove in which it is mounted, but it will be understood that said key 12 is slightly narrower than the groove in which it is seated when the piston is mounted in the cylinder, so that there may be proper provision for the compression of the piston when it becomes heated in the course of operation.

The nut 17 may be prevented from turning by the employment of a holding device, one form of which is illustrated in Fig. 7, and which consists of a spring 21 mounted in a notch or seat in the head of the piston and engaging one of the side walls.

The order of procedure as to the formation 50 of the piston may be varied in many respects without departure from the scope of the invention as set forth in the appended claims.

What I claim and desire to secure by Letters Patent, is:—

1. The process of making a piston, which consists in forming a hollow piston body with a lower ring, an upper ring and a top plate which are integrally united; splitting 60 the upper ring and the top plate to form segmental sections; and finishing the piston to a size in which the upper ring is of the same diameter as the diameter of the cylinder for which the piston is intended and the remaining portion of the piston is of smaller diam-

eter than the diameter of the cylinder for which the piston is intended.

2. The process of making a piston, which consists in forming a hollow piston body composed of a lower ring, an upper ring, 70 and a top plate which are integrally united; dividing the upper ring and the top plate into segmental sections integrally connected with the lower ring; compressing said sections toward each other to place the material 75 under tension; and finishing the piston while under tension to a size in which the segmental sections of the upper ring while compressed are of a size equal to the size of the diameter of the cylinder for which the piston is intended, and which when released from the tension will expand to a size in excess of the diameter of the cylinder for which the piston is intended.

3. The process of forming a piston, which 85 consists in forming a hollow piston body composed of a lower ring, an upper ring, and a top plate which are integrally united; dividing the upper ring and the top plate into segmental sections integrally connected 90 with the lower ring; compressing said sections toward each other to place the material under tension; finishing the piston while under tension to a size in which the segmental sections of the upper ring while compressed are of a size equal to the size of the diameter of the cylinder for which the piston is intended, and which when released from the tension will expand to a size in excess of the diameter of the cylinder for 95 which the piston is intended; and finishing the remaining portion of the piston to a size less than the diameter of the cylinder for which the piston is intended.

4. The process of making a piston, which 105 consists in forming a hollow piston body with a lower ring, an upper ring, and a top plate which are integrally united; splitting the top plate and the upper ring into segmental sections; placing the material of the piston body under tension by drawing the sections of the upper ring and the top plate toward each other; finishing the upper ring and top plate while the material is under tension to a size equal to the diameter of the cylinder for which the piston is intended; and closing the spaces between the segmental sections.

5. The process of making a piston, which 120 consists in forming a hollow piston body composed of a lower ring, an upper ring, and a top plate which are integrally united; splitting the upper ring and the top plate into segmental sections; placing the material under tension by drawing the segmental sections of the upper ring and top plate toward each other; finishing the upper ring and top plate while the material is under tension to a size equal to the diameter of the cylinder for which the piston is intended; and closing the spaces between the segmental sections.

tended; removing the tension from the material to permit the segmental sections to expand; and closing the spaces between the segmental sections of the top plate.

- 5 6. The process of making a piston, which consists of forming a piston body composed of a lower ring, an upper ring, and a top plate which are integrally united; splitting the upper ring and the top plate into segmental sections; drawing the segmental sections of the top plate and the upper ring toward each other to place the material under tension; finishing the top plate and upper ring to a diameter equal to the diameter 30 of the cylinder for which the piston is intended while the material is under tension; finishing the lower portion of the piston body to a size less than the diameter of the cylinder for which the piston is intended; 35 15 20 removing the tension to permit the segmental sections of the top plate to expand so that when the piston is placed in a cylinder the periphery of the upper ring will be pressed against the cylinder wall by the 40 resiliency of the material; and closing the 45 25 spaces between the segmental sections of the top plate.

JOHN FLAMMANG.
